UNITED STATES PATENT OFFICE.

JEROME NICHOLS HUMPHREYS, OF DALLAS, TEXAS.

CRIMPING-MACHINE.

1,149,520.

Specification of Letters Patent. Patented Aug. 10, 1915.

Application filed April 19, 1911, Serial No. 622,110. Renewed May 20, 1915. Serial No. 29,436.

To all whom it may concern:

Be it known that I, JEROME N. HUMPHREYS, residing at Dallas, in the county of Dallas and State of Texas, have invented 5 certain new and useful Improvements in Crimping-Machines, of which the following is a specification.

This invention relates to that class of machines more especially designed for crimping 10 the edges of covers or lids for lard pails and the like, and it primarily has for its object to provide a means of the character stated of a simple and economical construction that can be readily adjusted and manipulated 15 for the intended purposes.

With other objects in view, that will hereinafter appear, this invention comprises certain improvements in which is included a peculiar and novel arrangement of a 20 means for holding the lid or cover upon the body of the can, or other vessel to which the said cover is to be applied, a plurality of differently shaped crimping members for engaging, turning and crimping the edges 25 of the said cover, a revolving carrier that supports the crimping members, and means for successively bringing the differently shaped crimping members into action, all of which will be hereinafter fully explained, 30 specifically pointed out in the appended claims and illustrated in the accompanying drawings, in which:

Figure 1, is a side elevation of a machine embodying my invention, the crimping mechanism being shown at the elevated or inoperative position. Fig. 2, is a front elevation of the reciprocable shaft or support and the attached crimping devices, a plain face crimpler being shown in position 40 for making the first or initial crimp on the edge of the cover or lid. Fig. 3, is a similar view, the plain face crimpler being shown as having reached the limit of its inthrust and another crimpler shown as applying the finishing crimp to the cover or lid edge. Fig. 4, is a detail sectional view of one of the crimping rollers and its adjusting devices. Fig. 5, is a detail view of the hand wheel adjustment for the foot lever stop devices. Fig. 6, is a cross section of the crimping mechanism hereinafter specifically referred to.

In the practical arrangement of my invention, the same includes a bed plate or 55 table 1 on which the pail, or other vessel to

be crimped, is set during the operation of applying the cover thereto.

In the drawing is shown a bed plate 1 mounted on an upright frame 2, the upper end of which supports the crimping mechanism, the construction of which forms the essential feature of my invention.

The crimping mechanism comprises a tubular member 31 the upper end of which is connected (in any suitable manner) to a cross plate B, the said upper end being shown as externally threaded to screw into a threaded passage in the said cross plate or bar B, see Figs. 1, 3 and 6.

The lower end of the member 31 is closed by a solid head plate 33 that engages with ball bearings 35 supported in the ball race 36 that is formed in the top of a swiveled head D. The head D has a pendent shank d and to the said shank is attached a presser head E that is utilized to hold the cover or lid, to be crimped, down on the pail or vessel, during the operation of crimping the said lid thereon, it being understood that different sizes of heads E are used to suit the different diameters of the pails or vessels to which the covers or lids are to be applied.

F is a collar that is clamped on the said lower end of the member 31 for controlling the tension of a coil spring S held on the member 31 and its function is to force a second cross bar C upwardly when the shaft A is released, as will be presently explained.

Cross bar C has two sets of apertures c—c, and it also has a central hub c' for slidably engaging the member 31, and the said hub is transversely apertured as at c² to receive a locking pin c³ that passes through vertically elongated slots 32 in the shaft A, and through the lower end of the shaft A, the said connection of parts providing for the raising and lowering of the cross bar C with the shaft A when the latter is moved vertically.

The upper end of the shaft A is slidably journaled in bearing boxes 14—14 mounted on the horizontally slotted head portion 21 of the main supporting frame and the said upper end of the shaft carries a sleeve 9 that is adjustably mounted thereon and which is joined with the shaft by a key pin 11 that passes through one of a series of holes 12 in the shaft, which holes are provided for setting the operating parts to suit 110

the height of the pail or other vessel to be covered.

8 designates a clutch ring that is mounted on the sleeve 9 and which has trunnions 5 80—80 for engaging with the forked bearing ends 71 of a rocker arm 70 fulcrumed at 7 on the head 21 of the main frame and whose rear end carries a counterpoise for counterbalancing the weight of the shaft A 10 and the crimping mechanism carried thereby. A spring 13 is also provided that joins with the main frame and the rocker bar 70 for assisting in bringing the said bar back to a normal position.

15 The cross bar B, before referred to, has two sets of apertures b—b that correspond with the apertures in the upper end of the shaft and the two or more sets of apertures c—c in the bar C for setting the crimping 20 mechanism to operate on cover lids of different diameters.

25 G'—G² are two hanger arms that are pivotally hung from the cross bar B by the pins g'—g² that engage the selected ones of the apertures b in the said bar B.

The hanger arm G², has a slot g⁵ which has a portion g⁴ in parallelism with the longitudinal axis of the arm, and which has also a lower portion g⁵ that extends outwardly at an obtuse angle to the said upper portion g⁴ and in the said compound slot g⁵—g⁴ plays a stud c⁵ that projects from and is held in a selected one of the apertures c in the bar C.

35 Hanger arm G' is also formed with a slot having angle portions g⁶—g⁷ for receiving the stud c⁶, as best shown in Figs. 2 and 3, and it should be here stated that the slots in the arms G'—G² are relatively so formed with

40 respect to each other that in descending the bar C first swings the arm G' inwardly and in advance of bringing the arm G² inwardly whereby to bring the crimping roller W', mounted on the lower end of the said arm 45 G' into active engagement with the edge of the lid to be crimped, so as to turn the said lid edge down before the roller W' on the other arm G² is swung into position for applying the final crimping operation to the 50 said lid.

The crimping rollers W'—W² are removably mounted on the heads of screw pins H—H that thread into screw sockets h—h in the lower ends of the arms G'—G² and 55 they are held by lock nuts h'—h'. h—h indicate jam nuts for holding the rollers W—W² on the heads of the said pins H—H.

In the practical application of my invention, the crimping rollers are shaped to suit the character of the crimps to be made. In the drawings, the roller W' is shown with a plane incline face for simply engaging the lid edge and bending it down over the upper 65 edge of the pail, as shown in Fig. 2. Roller

W² is so curved that it crimps the turned down edge under the edge of the pail mouth, the latter being also turned outwardly and held there to form a solid bearing (against which the lid edge is crimped) by the 70 presser plate E, the lower edge e and the under face of which is suitably shaped to form the solid bearing edge, as is clearly shown on Figs. 2 and 3.

For manually actuating the shaft A and 75 the crimping mechanism that is suspended thereon, a foot lever 5 is provided which is fulcrumed at 50 on the base of the frame 2 and is connected to a lift rod 51 which pivotally joins with a rocker arm 70, mounted 80 on top of the framing 2.

For limiting the up-thrust of the lever 5, a stop block 4 is mounted upon a threaded shaft 3 having a bearing at the lower end on the base frame 2 and a bearing at the upper end in the under side of the bed plate 1, it also having a fixedly attached hand wheel 30.

By turning the hand wheel 30, in either direction, and holding the stop 4 from turning 90 with the shaft 3, the said stop can be raised or lowered to the position desired, it being understood that the said stop regulates the up-throw of the lever 5 and the corresponding drop of the shaft A with the crimping 95 mechanism.

Motion is imparted to the shaft A in any approved manner, for example, in the drawings a pulley wheel 25 is keyed on the shaft A, located in the slotted head portion 21 of the main frame and with which engages a drive belt 26 that takes over a drive pulley 27 on the upper end of a drive shaft 28, in practice preferably driven by a motor 29.

The operation of my invention is best explained as follows: The lid or cover is placed upon the mouth of the pail, and it is held thereon by bringing the crimping mechanism down to the operative position, which is done by depressing the lever 5 which, through the rocking shaft 70 moves the shaft A down and in consequence the crimping devices are lowered or dropped until the presser plate E engages and holds the lid solid upon the upper edge of the pail and 105 when this occurs the further down movement of the cross member B and its hanger arms G'—G² is arrested, it being understood that the cross arm or member C is connected with the shaft through the medium of the locking pin c⁵ which has free movement vertically, in the oppositely disposed slot 32 in the tubular member 31. By reason of the

down movement of the member 31 and the arm B being checked after the presser head E engages the lid, the final movement or drop of the shaft carries the pin c⁵ and the cross member C farther down and thereby 110 causes the arms G'—G², that carry the crimping rollers W'—W² respectively, to swing 115

120 in the direction of the arrow in Fig. 2, so as to bring the roller W' into engagement with the lid edge and the roller W² into engagement with the edge of the pail mouth, the latter being turned outwardly and held by the 125 presser plate E, the lower edge e and the under face of which is suitably shaped to form the solid bearing edge, as is clearly 130 shown on Figs. 2 and 3.

inwardly and since the slot and pin construction for the arm G' is arranged to operate in advance of the like parts for the arm G², the edge of the lid is first bent over the upper edge of the pail by the roller W', see Fig. 2, which brings the partial or initial crimp of the said lid in position to be engaged by the roller W², see Fig. 3, which then completes the crimping operation, it being further understood that the intrust of the roller W' is checked before the roller W² begins the final crimping operations.

What I claim is:

1. In a crimping machine, a longitudinally movable and a rotatably mounted shaft, a lower cross bar fixed to the said shaft, an upper cross bar loosely mounted on the said shaft and rotatable therewith, a presser member loosely mounted on the shaft and connected to move with the said upper cross bar, a plurality of crimping arms carried by the said upper cross bar, co-operating connections between the said arms and the lower cross bar and co-operating connections between the shaft and the presser member carrying bar in virtue of which as the said shaft is moved longitudinally in one direction, the said upper cross bar is moved to bring the presser member in contact with the work and upon further movement of the said shaft in the same direction, the said lower cross bar is moved farther away from the said upper cross bar to thereby swing the crimping arms toward the work and crimping elements carried by the said arm.
2. In a crimping machine, a longitudinally movable and a rotatably mounted shaft, crimping mechanism mounted upon the said shaft to rotate therewith, the said mechanism including an upper cross bar loosely mounted on the shaft, a lower cross bar fixedly mounted upon the said shaft, a plurality of crimping arms, crimping devices mounted thereon, the said arms being pivotally hung from the upper cross bar, a presser member carried by the upper cross bar, the aforesaid elements being coöpera-

tively connected whereby on a downward movement of the shaft the presser member is first caused to engage the work and upon further downward movement of the said shaft the crimping arms are swung inwardly to move the crimping devices into an operative position.

3. In a crimping machine; a longitudinally movable and rotatably mounted shaft, a crimping mechanism carried by the shaft to rotate therewith, the said mechanism including an upper cross bar loosely mounted on the shaft, the lower cross bar fixedly mounted on the said shaft, a plurality of crimping arms, a crimping device mounted on each of the said arms, the said arms being pivotally hung from the upper cross bar, a presser member carried by the upper cross bar, coöperative connections between the lower cross bar and the said arms, adapted for moving the crimping devices to their operative positions and for continuing the movement of one of the said devices after the other of the said devices has completed its work.

4. In a crimping machine, a longitudinally and rotatably mounted shaft, a tubular member mounted upon the shaft and in which the said shaft has free movement, said tubular member having oppositely disposed longitudinal slots, a lower cross arm mounted upon the tubular member, and connected to the shaft to move therewith, an upper cross arm mounted upon the tubular member to move therewith, a presser on the lower end of the tubular member, crimping mechanism including at least one arm pivotally supported on the upper cross head, said arm having a longitudinal slot provided with an angle portion, a key mounted in the lower cross arm that projects into the said slot, and a crimping device carried on the lower end of the pivoted arm.

JEROME NICHOLS HUMPHREYS.
